pany, Wickliffe, Ohio, a corporation of Ohio

Application November 6, 1944, Serial No. 562,234

17 Claims. (Cl. 212—21)

1

The present invention relates to overhead operator's enclosures or cabs and, more particularly, to operator's cabs for overhead traveling cranes.

Because crane operators are required to work at high elevations in all types of factories, etc., they are exposed to extremes of heat and cold, and to all sorts of gases, smoke, fumes, etc., some of which may be very injurious to their health, and the principal object of the present invention is the provision of a novel and improved operator's enclosure or cab for an overhead traveling crane within which it will be safer and more comfortable for the operator to work.

Other objects of the invention are the provision of a novel and improved operator's enclosure or cab for an overhead traveling crane which will enclose the operator without unduly obstructing his vision, thus providing him with a safe, comfortable and convenient place within which to work.

Another object of the invention is the provision of a novel and improved operator's enclosure or cab of the character referred to having a large portion of the side walls composed of transparent material, and so constructed and arranged that the transparent side wall sections can be readily cleaned both inside and outside.

Another object of the invention is the provision of a novel and improved overhead operator's enclosure or cab of the character referred to, which is generally cylindrical in shape, has a large proportion of the side walls composed of transparent material, and comprises a rotatable platform for facilitating the cleaning of the outside of the transparent side wall sections.

Another object of the invention is the provision of a novel and improved operator's enclosure or cab for an overhead traveling crane which is small enough to be readily cooled or otherwise air conditioned.

Another object of the invention is the provision of a novel and improved generally cylindrical operator's enclosure or cab for an overhead traveling crane, the side walls of which are composed largely of transparent material, and which comprises an operator's seat having the bridge, trolley and hoist controls arranged thereabout within easy reach of an operator seated therein.

Another object of the invention is the provision of a novel and improved overhead traveling crane and the like comprising an operator's cab or enclosure of the character aforesaid.

The invention resides in certain constructions and combinations and arrangements of parts and

2

further objects and advantages will be apparent to those skilled in the art to which it relates from the following description of the preferred embodiment described with reference to the accompanying drawings forming a part of this specification in which similar reference characters designate corresponding parts, and in which

Fig. 1 is a fragmentary perspective view of an overhead traveling crane embodying the present invention;

Fig. 2 is a sectional view approximately on the line 2—2 of Fig. 1;

Fig. 3 is a fragmentary plan view of the crane shown in Fig. 1;

Fig. 4 is a section approximately on the line 4—4 of Fig. 5;

Fig. 5 is a sectional view approximately on the line 5—5 of Fig. 4, with portions in elevation and other portions omitted for clearness;

Fig. 6 is a plan view of the cab proper; and

Fig. 7 is an enlarged sectional view approximately on the line 7—7 of Fig. 6, with portions omitted for clearness.

An overhead crane operator's work is very exacting, requires constant attention and an unobstructed view of a large portion of the factory or space within which the crane operates. On the other hand, the operator's location, generally adjacent to the roof of a factory building where he is subject to all conditions of heat, smoke, gases, fumes, etc., is not conducive to comfort, etc., and prior attempts to enclose the operator and thus make him more comfortable have proved unsuccessful for various reasons, such as, the operator's view was unduly obstructed; it was impracticable, if not impossible, to keep the outside of the transparent wall sections of the enclosure clean; the enclosure was too large to permit air conditioning, including cooling

or heating, as the case might be, since the air conditioning unit must be carried on the crane which is normally located either inside a building near the roof where the temperature is high, or outside where it is subject to extreme tem-

peratures both hot and cold; etc. Without further discussion, it will be seen that in the devising of a satisfactory overhead operator's enclosure or cab and particularly one intended to be used with an overhead traveling crane, the inventor is confronted with numerous problems, many of which are not apparent upon cursory consideration of the matter.

Although the present invention is susceptible of numerous embodiments, it is particularly applicable to overhead traveling cranes and is herein

shown and described as embodied in an overhead traveling crane. The construction of the crane, aside from the cab, may be that of any well-known commercial overhead crane and the showing thereof in the drawings is more or less diagrammatic. Only those parts are shown and described which are necessary to an understanding of the present invention.

Referring to the drawings, the crane shown therein comprises a crane trolley A movable along a crane bridge B, which bridge is, in turn, movable along crane runways comprising rails 10 located at opposite ends of the bridge and fixed to the building or structure C within which the crane is housed. The crane trolley A is supported by wheels 11 upon rails 12 on the bridge B and is adapted to be moved in opposite directions along the bridge B by a reversible electric trolley travel motor 13 located on the trolley and connected to one or more of the wheels 11. The bridge B is adapted to be moved in opposite directions along the crane runway by a reversible electric bridge travel motor 14 located on the bridge and connected by mechanism, including a shaft 15, to a plurality of the wheels 16 of the end trucks 17, which wheels support the bridge on the rails 10 of the crane runway. In addition to the trolley travel motor 13, the trolley comprises a reversible hoist motor 20 operatively connected to the cable drum 21 and adapted to rotate the same in opposite directions to take up or let out the load cable 22 and, in turn, raise or lower the crane hook 23 supported thereby.

The crane bridge comprises two spaced girders 24, 25, opposite ends of which are supported on the end trucks 17, and the construction of the hoist mechanism is such that the load cable 22 extends downwardly between the girders. As is also usually the case with cranes of the character referred to, the bridge is provided with a walkway along one side for the purpose of facilitating inspection and maintenance of the equipment thereon. As shown, the walkway comprises a floor 26 supported upon a plurality of projecting T-irons 27 welded to the outside of the left-hand girder, as viewed in Fig. 2, and a hand rail 28 spaced from the girder. The bridge travel motor 14 is also preferably provided with a hydraulic brake 30 or some similar device for helping to control the movement of the bridge. The construction thus far described is well known in the art and per se forms no part of the present invention.

The actuation of the trolley travel motor 13, the bridge travel motor 14, the hoist motor 20, and the application and release of the hydraulic brake 30 are manually controlled from an operator's cab D, which cab is an air conditioned, generally cylindrical enclosure or housing having transparent side walls suspended from one end of the bridge and offset from the centerline thereof so as to allow the load cable and crane hook to pass thereby. The electrical connections between the manually operated control devices 31, 32 which control the actuation of the trolley travel motor 13 and the hoist motor 20, respectively, include the trolley and trolley collectors 33, 34 and are made in a manner well known in the art. The operation of the bridge travel motor 14 is controlled by the foot-operated controller 35.

The cab proper is preferably approximately four feet in diameter and is suspended from the crane bridge with its longitudinal axis extending vertically by a plurality of brackets 36 welded thereto and to a convenient part of the bridge B. As previously stated, the side walls of the cab are largely formed of transparent material so that the

operator has substantially an unobstructed view of the area within which the crane operates. As shown, the frame of the cab is made of welded-up structural steel members and steel plates and the floor comprises a disk-like steel plate 37 resting upon and welded to the upper side of a substantially cylindrical U-shaped channel member 38, the opposite ends of which are welded to horizontal U-shaped channel members 40, 41 extending parallel with the center line of the crane bridge. The forward ends of the members 40, 41 are welded to radial ribs 42, 43 located underneath the floor 37, which ribs are, in turn, welded thereto and to the circular member 38 and to a cylindrical boss 44 located below the floor 37 and positioned coaxially with the longitudinal axis of the cab proper. The floor 37 is further reinforced by a plurality of radially extending ribs 45, 46 connected thereto and to the channel 38 and the tubular member 44 in a manner similar to that in which the ribs 42, 43 are connected thereto. In addition to the foregoing, the rear part of the floor 37 is supported by a U-shaped channel member 47 extending between the members 40, 41 and connected thereto approximately midway between their ends. From the channel member 47, the members 40, 41 extend to the rear of the cab proper and form a combination closure and support for a ladder assembly, designated generally as E, and a cabinet, designated generally as F. The assembly E affords access to the walkway 26 and the cabinet houses the air conditioning equipment, etc.

The roof of the cab proper comprises a generally disk-like plate 50 welded to the upper edge of a substantially cylindrical steel plate 51, a portion of which is cut out as at 52, to help form the doorway leading into the cab. The floor 37 of the cab, including the channel members 38, 40, 41, etc., is suspended from or connected to the steel plate 51 at the top of the cab by cross-shaped rods 53, 54, 55, 56, the upper ends of which are welded to the member 51 while the lower ends are welded to the floor plate 37 and the channel member 38. Opposite ends of the member 51 are welded to the inside webs of vertically positioned channel-shaped members 57 and 58, the upper ends of which are also welded to the ceiling plate 50. The lower ends of the members 57, 58 rest upon the horizontal channel members 40, 41, respectively, are welded thereto, and assist in connecting the top and bottom frame portions of the cab together. The rods 53, 54, 55, 56 are equally spaced with respect to each other and the members 57, 58 and the side wall sections or panels 60, 61, 62, 63, 64 intermediate said members and rods are formed of curved transparent material, such as, glass or the like, the curvature of which conforms to the diameter of the cab proper, thus forming a substantially cylindrical cab.

The cross-shaped rods 53 to 56 extend to the roof of the cab and the external flanges at the top are cut away to accommodate the member 50. The vertical edges of the transparent wall sections 61, 62, 63 lie in the angle formed by the external flanges of the rods 53 to 56 and are held in assembled relation therewith by metal glazing clips 65 secured to the external flanges of the rods. The rear vertical edge of the transparent panel 64 is secured to the member 53 by a strip 66 carried thereby and having a portion overlying the edge of the panel. The upper edges of the transparent panels abut the lower edge of the member 51 and the lower ends of the panels rest upon the channel member 38 between the

floor plate 37 and the member 67 encircling the lower edges of the panels 60 to 64 and welded to the top of the member 38 and to the lower ends of the members 54, 55, 56, 58. The overall height of the cab shown is approximately six feet and the transparent wall sections are approximately five feet high and extend entirely around the cab except for the portion thereof intermediate the vertical members 57, 58, which members are preferably spaced about a foot and a half or two feet apart.

The disk-shaped steel plate 50 which forms the roof of the cab is reinforced by a plurality of radially extending webs 70 welded thereto and to a tubular member 71 located in an aperture formed in the center of the plate 50. The top of the cab is further reinforced by a frusto-conical shaped plate 72 having a plurality of apertures 73 therein, which plate is welded to the inside of the member 51 and to the underside of the roof plate 50. The construction is such that a duct 74 is formed around the top of the cab, which duct is employed to admit air to the interior of the cab in a manner hereinafter more specifically described.

The transparent section or panel 60 remote from the bridge B and towards the rear of the cab proper is preferably so constructed and supported that it constitutes a door for closing the doorway. For this purpose it is suspended from the top of the cab proper by a sector-like bracket 76 pivotally supported by the sleeve 71 by means of a bolt 77 projecting through the radial inner end of the bracket and rotatably supported in the sleeve. The lower end of the transparent wall section or door 60 engages within a groove formed in the upper side of an arcuate-shaped member 81 fixed to the floor plate 37. Resilient members or gaskets 82 are provided along opposite sides of the doorway so as to make the opening substantially air-tight when the door 60 is closed. Inside and outside handles 83, 84 are provided for facilitating opening and closing of the door.

The provision of the door 60 allows the operator to go back and forth between the interior of the cab proper and a platform G located outside of the cylindrical enclosure. The platform G comprises a steel plate 85 welded to the top of the outer end of a U-shaped channel member 86, the inner end of which is offset downwardly with respect to the outer end and is pivotally connected to the member 44 by a bolt or pin 87, the shank of which projects upwardly into the tubular member. The platform is supported by a pair of tapered rollers 88 rotatably supported on the inner ends of radially extending shafts 90 fixed in members 91 secured to a vertical plate 92 interposed between the radial inner edge of the plate 85 which is arcuate-shaped to conform to the curvature of the cab proper and the channel member 86. The rollers 88 engage within the groove of the circular U-shaped channel member 38 which forms a trackway for the rollers.

Without further description, it will be apparent that the platform G can be moved or rotated about the longitudinal axis of the cab proper to any position exteriorly of the transparent wall sections or panels and the outside thereof readily cleaned. As shown, the platform is generally rectangular in shape except for the part which is cut out to accommodate the cab proper and the open sides thereof are provided with a guard rail 93, one section 94 of which is in the form of a gate so that the operator

can enter the cab by way of the platform G from a stationary loading platform H located at one end of the crane runway and fixed to the structure C within which the crane is housed. The platform G is normally retained in the position in front of the door 60 by a hook 95 connected to the guard rail 93 and to the member 57.

The space between the channel-shaped uprights 57, 58, previously referred to, is normally closed by the assembly E by means of which the operator can go directly from the interior of the cab to the crane walkway and vice versa. The assembly E is formed by a flanged channel-shaped member 100 closed at both ends and provided with a plurality of steps in the form of rods or rungs 101 extending across the front. The lower end of the member 100 is pivotally connected by a rod 102 and brackets 103 to the lower ends of the members 57, 58 and when in the position shown in Figs. 4, 5 and 6, forms a substantially air-tight closure for the opening in the cab intermediate the members 57, 58. A suitable gasket can be employed, if desired. The member 100 is located underneath an opening 104 in the floor 26 of the walkway and when the member 100 is moved from the vertical position shown in Fig. 5 to the inclined position shown in dot-dash lines in the same figure, the operator can readily go from the cab to the crane walkway or vice versa.

Any suitable means may be employed to hold the member 100 in vertical position, such as, the hook 105 shown, which hook is pivotally connected to the member 58 and adapted to engage over one of the rungs 101. Rotation of the assembly E in a counter-clockwise direction, as viewed in Fig. 5, is limited by a horizontal angle iron 106 extending across the back of the cabinet F and behind the member 100 where it is connected to the upper end of a vertical angle iron 107, the lower end of which is welded to the member 41. The upper end of the member 107 is connected by an angle iron 108 to the member 51 adjacent to the member 58. An angle iron 109, extending diagonally between the members 107 and 41 helps to brace the frame, and a plurality of horizontal bars 110 and 111 connected to the brace 109 and to the member 58, eliminate any possibility of the operator falling out of the cab when the assembly E is in its inclined position.

The cabinet F is supported upon two horizontal channel members 112 and 113 resting upon and secured to the rear ends of the members 40, 41. The cabinet is preferably made of sheet metal and may be of any desired form or size. As shown, it is divided in two compartments by a horizontal partition 114, which compartments are accessible through suitable doors.

As previously stated, provision is made for air conditioning the cab. Preferably, air which has been cleaned, humidified and cooled is admitted to the top of the cab through the apertures 73 in the plate 72 and a slight pressure is maintained in the cab so as to prevent the entrance of unconditioned air around the door 60, etc. Any desired arrangement of apertures may be employed. Preferably, the arrangement is such that air is admitted into the cab without subjecting the operator to undesirable drafts, etc. The air conditioning apparatus is preferably housed within the cabinet F, previously referred to, and located to the opposite side of the assembly E from the crane bridge and behind the platform G when in its normal position. Any commercial air conditioning equipment, designated generally 75 as 115, may be employed and, in the embodiment

shown, the conditioned air is conducted from the exit of the air conditioning equipment to the duct 74 formed by the plate 72 by a conduit 116 communicating with the upper near front corner of the cabinet F and the end of the duct 74 adjacent to the door 60.

Alternatively, suitable means other than that shown in the drawings may be employed for conducting the conditioned air from the air conditioning equipment to the interior of the cab. In the embodiment shown, no air return is employed between the cab and the air conditioning equipment, however, a return air duct may be supplied, if desired. Because the cab is usually located adjacent to the roof of the factory building where the temperature is ordinarily above normal, the efficiency of the air conditioning equipment is low, but the fact that the volume of the cab is small, makes it possible to air condition the same.

The cab is preferably suspended from the crane bridge in the relative position shown in the drawings, with the rear side of the cabinet F just clearing the side of the crane runway supporting structure adjacent thereto, and with a line connecting the longitudinal axis of the cab proper and the center of the ladder extending parallel with the length of the crane bridge. The cab is also offset to one side of the centerline of the bridge so that the load cable and crane hook can pass beside the cab.

The operator sits in a stationary chair or seat 120, the center of which is slightly behind and to the bridge side of the center of the cab proper and, when seated in this position, has a substantially unobstructed view of the area over which the crane operates and of other cranes which may be operating on the same crane runway or in the same area. By leaning backwards and turning his head slightly, the operator can see the crane hook even though it is behind him. Any desired controls may be located in the cab other than the controls shown which, in addition to the hand-operated reversing controllers 31, 32 located at opposite sides of the operator's seat 120 for controlling the trolley travel and hoist motors, respectively, and the foot-operated controller for the bridge travel motor, comprise a foot-operated hydraulic brake master cylinder unit 121, including the foot pedal 122, for the brake 30. In view of the fact that the operator is required to use both hands and both feet, the seat is preferably made stationary, as previously mentioned. If different control mechanism is employed, it may be desirable to have the operator's seat movable. If the operator is of normal height, his eyes will be about 4' or 4½' above the floor 37 and since the diameter of the cab proper is preferably approximately 4', it will be apparent that with little, if any, movement on his part, he can look down at any angle of from 15° to 20° with the vertical.

While the preferred embodiment of the invention has been described with considerable detail, it will be apparent that the invention is not limited to the particular construction shown, however, it will be apparent that the objects heretofore enumerated and others have been accomplished and that there has been provided a novel and improved overhead operator's enclosure or cab and particularly an overhead traveling crane cab in which the operator, although comfortably seated and wholly enclosed, has a substantially unobstructed view of the entire working area. In addition, the cab includes means for conveniently cleaning the outside of

the transparent wall sections. This feature of the present construction is particularly important because unless the transparent wall sections or panels are maintained clean, the operator's view will be unduly restricted and unless provision is made for readily cleaning the outside of the transparent wall sections, they will not be cleaned as needed.

As previously stated, the invention is not limited to the particular construction shown and it is my intention to hereby cover all adaptations, modifications and uses thereof which come within the practice of those skilled in the art to which the invention relates and within the spirit and scope of the appended claims.

Having thus described my invention, what I claim is:

1. An overhead operator's cab comprising a generally cylindrical tubular member having the side walls thereof composed largely of transparent material, means for supporting said member with the longitudinal axis thereof extending vertically, and a platform movably connected to said member for rotation about the exterior thereof.

2. An overhead operator's cab comprising a generally cylindrical tubular member having the side wall thereof composed largely of transparent material, means for supporting said member with the longitudinal axis thereof extending vertically, a platform movably connected to said member for rotation about the lower end thereof, and a door in the side wall of said member providing access to said platform.

3. An overhead operator's cab comprising a substantially air-tight generally cylindrical tubular member having sides thereof composed largely of transparent material, means for supporting said member with the longitudinal axis thereof extending vertically, a platform movably connected to said member for rotation about the lower end thereof, a substantially air-tight door in one side of said member for permitting access to said platform, and an operator's seat within said member.

4. In a multimotored, electrically operated, overhead traveling crane, the combination of: a movable bridge; a trolley movably supported on said bridge; hoisting mechanism including a load cable carried by said trolley; individual electric motors for moving said bridge, trolley and hoisting mechanisms; an operator's cab comprising a generally cylindrical tubular member closed at both ends and having the side walls thereof composed largely of transparent material; means for suspending said cab from said bridge adjacent to one end thereof with the longitudinal axis of said tubular member extending vertically and said cab offset with respect to the vertical longitudinal centerplane of said bridge so that the load cable of the hoisting mechanism can pass thereby; an operator's seat located in said tubular member slightly to the rear of the center thereof and offset from the center toward the side adjacent to the vertical longitudinal centerplane of said bridge; and manual control devices adapted to control said electric motors for effecting a variety of movements of said bridge, trolley and hoisting mechanisms; said manual control devices being located in said tubular member within easy reach of an operator seated in said seat.

5. In a multimotored, electrically operated, overhead traveling crane, the combination of: a movable bridge; a trolley movably supported on said bridge; hoisting mechanism including a load cable carried by said trolley; individual elec-

tric motors for moving said bridge, trolley and hoisting mechanisms in opposite directions; an operator's cab comprising a generally cylindrical tubular member closed at both ends and having the side walls thereof composed largely of transparent material; means for suspending said cab from said bridge adjacent to one end thereof with the longitudinal axis of said tubular member extending vertically and said cab offset with respect to the vertical longitudinal centerplane of said bridge so that the load cable of the hoisting mechanism can pass thereby; a stationary operator's seat located in said tubular member slightly to the rear of the center thereof and offset from the center toward the side adjacent to the vertical longitudinal centerplane of said bridge; manual control devices located within easy reach of an operator seated in said seat for controlling said electric motors to effect a variety of movements of said bridge, trolley and hoisting mechanisms; a platform movably connected to said tubular member for rotation about the lower end thereof; and a door in the side wall of said tubular member providing access to said platform.

6. In a multimotored, electrically operated, overhead traveling crane, the combination of: a movable bridge; a trolley movably supported on said bridge; hoisting mechanism including a load cable carried by said trolley; individual electric motors for moving said bridge, trolley and hoisting mechanisms in opposite directions; an operator's cab comprising a substantially air-tight generally cylindrical tubular member closed at both ends and having the side walls thereof composed largely of transparent material; means for suspending said cab from said bridge adjacent to one end thereof with the longitudinal axis of said tubular member extending vertically and said cab offset with respect to the vertical longitudinal centerplane of said bridge so that the load cable of the hoisting mechanism can pass thereby; a stationary operator's seat located in said tubular member slightly to the rear of the center thereof and offset from the center toward the side adjacent to the vertical longitudinal centerplane of said bridge; manual control devices located within easy reach of an operator seated in said seat for controlling said electric motors to effect a variety of movements of said bridge, trolley and hoisting mechanisms; a platform movably connected to said tubular member for rotation about the lower end thereof; a door in the side wall of said tubular member providing access to said platform; means located outside of said tubular member for air conditioning the interior thereof; and means for connecting said last-named means with the interior of said member.

7. In a multimotored, electrically operated, overhead traveling crane, the combination of: a movable bridge; a trolley movably supported on said bridge; hoisting mechanism including a load cable carried by said trolley; individual electric motors for moving said bridge, trolley and hoisting mechanisms in opposite directions; an operator's cab comprising a substantially air-tight generally cylindrical tubular member closed at both ends and having the side walls thereof composed largely of transparent material; means for suspending said cab from said bridge adjacent to one end thereof with the longitudinal axis of said tubular member extending vertically and said cab offset with respect to the vertical longitudinal centerplane of said bridge so that the load cable of the hoisting mechanism can pass thereby; a

stationary operator's seat located in said tubular member slightly to the rear of the center thereof and offset from the center toward the side adjacent to the vertical longitudinal centerplane of said bridge; manual control devices located within easy reach of an operator seated in said seat for controlling said electric motors to effect a variety of movements of said bridge, trolley and hoisting mechanisms; a platform movably connected to said tubular member for rotation about the lower end thereof; a door in the side wall of said tubular member providing access to said platform; means located outside of and to the rear of said tubular member for air conditioning the interior thereof; a walkway on said bridge above said tubular member; said tubular member having an aperture in the side thereof behind said operator's seat; a ladder extending between the lower end of said tubular member and said walkway accessible through said aperture; and movable means for closing said aperture.

8. In a multimotored, electrically operated, overhead traveling crane, the combination of: a movable bridge; a trolley movably supported on said bridge; hoisting mechanism including a load cable carried by said trolley; individual electric motors for moving said bridge, trolley and hoisting mechanisms in opposite directions; a brake for said bridge; an operator's cab comprising a generally cylindrical tubular member closed at both ends and having the side walls thereof composed largely of transparent material; means for suspending said cab from said bridge adjacent to one end thereof with the longitudinal axis of said tubular member extending vertically and said cab offset with respect to the vertical longitudinal centerplane of said bridge so that the load cable of the hoisting mechanism can pass thereby; a stationary operator's seat located in said tubular member slightly to the rear of the center thereof and offset from the center toward the side adjacent to the vertical longitudinal centerplane of said bridge; manual control devices located within easy reach of an operator seated in said seat for controlling said electric motors and said brake to effect a variety of movements of said bridge, trolley and hoisting mechanism; said control devices consisting of two hand controls one at either side of said seat and two pedals in front of the operator's seat one of which controls the application of the bridge brake; a platform movably connected to said tubular member for rotation about the lower end thereof; and a door in the side wall of said tubular member providing access to said platform.

55. 9. In a multimotored, electrically operated, overhead traveling crane, the combination of: a movable bridge; a trolley movably supported on said bridge; hoisting mechanism including a load cable carried by said trolley; individual electric motors for moving said bridge, trolley and hoisting mechanisms in opposite directions; a brake for said bridge; an operator's cab comprising a generally cylindrical tubular member closed at both ends and having the side walls thereof composed largely of transparent material; means for suspending said cab from said bridge adjacent to one end thereof with the longitudinal axis of said tubular member extending vertically and said cab offset with respect to the vertical longitudinal centerplane of said bridge so that the load cable of the hoisting mechanism can pass thereby; a stationary operator's seat located in said tubular member slightly to the rear of the center thereof and offset from the center toward the side adjacent to the vertical longitudinal centerplane of

11

said bridge; manual control devices located within easy reach of an operator seated in said seat for controlling said electric motors and said brake to effect a variety of movements of said bridge, trolley and hoisting mechanisms; said control devices consisting of two hand controls one at either side of said seat and two pedals in front of the operator's seat one of which controls the application of the bridge brake; a platform movably connected to said tubular member for rotation about the lower end thereof; a door in the side wall of said tubular member providing access to said platform; means located outside of said tubular member for air conditioning the interior thereof; a walkway on said bridge above said tubular member; said tubular member having an aperture in the side thereof behind said operator's seat; a ladder extending between the lower end of said tubular member and said walkway accessible through said aperture; and movable means for closing said aperture.

10. In a multimotored, electrically operated, overhead traveling crane, the combination of: a movable bridge; a trolley movably supported on said bridge; hoisting mechanism including a load cable carried by said trolley; power means for moving said bridge, trolley and hoisting mechanisms in opposite directions; an operator's cab comprising a generally cylindrical tubular housing closed at both ends and having the side walls thereof composed largely of transparent material; means for suspending said cab from said bridge with the longitudinal axis of said tubular housing extending vertically and said cab offset with respect to the vertical longitudinal center-plane of said bridge so that the load cable of the hoisting mechanism can pass thereby; a platform movably connected to said tubular housing for rotation about the lower end thereof; and a door in the side wall of said tubular housing providing access to said platform.

11. In an operator's cab for an overhead material handling device, a generally cylindrical tubular member having its longitudinal axis extending vertically and its side walls composed largely of transparent material, said member having an aperture permitting access by an operator to the interior thereof, means for closing said aperture, a platform connected to said member and movable about the lower end thereof, an operator's seat located within said member adjacent to the longitudinal axis thereof, and manual control devices adapted for effecting a variety of operations of the handling device, said manual control devices being fixed with respect to said seat and located within easy reach of an operator seated in said seat.

12. An operator's cab comprising a substantially air-tight generally cylindrical tubular member closed at both ends and having the sides thereof composed largely of transparent material, said member being adapted to be suspended from an overhead movable material handling device with the longitudinal axis thereof extending vertically, said tubular member having an aperture in a side thereof, and means connected to said member and constituting a ladder extending from adjacent to the bottom of said member to the top thereof for closing said aperture.

13. An operator's cab comprising a substantially closed generally cylindrical tubular member having the sides thereof composed largely of transparent material, said member being adapted to be suspended from an overhead movable material handling device with the longitudinal axis there-

12

of extending vertically, said tubular member having an aperture in a side thereof, a substantially channel-shaped member for closing said aperture, and means for pivotally connecting the lower end of said channel-shaped member to said tubular member, said channel-shaped member being open along the side thereof facing said member and having steps therein.

14. In an operator's cab for a multimotored, electrically operated, overhead traveling crane of the character described including a bridge provided with a walkway, the combination of a substantially closed generally cylindrical tubular member having sides thereof composed largely of transparent material, means for suspending said member from the bridge of the crane with the longitudinal axis thereof extending vertically, a platform movably connected to said member for rotation about the lower end thereof, a door in one side of said member for permitting access to said platform, an operator's seat within said member located slightly to the rear and to one side of the longitudinal centerline thereof, manual control devices for controlling the operation of the motors of the crane located in said member within easy reach of an operator seated in said seat, said member having an aperture in a side thereof and to the rear of said operator's seat, movable means connected to said member for closing said aperture, a ladder connected to said member and accessible through said aperture and adapted to permit communication by an operator between said member and the walkway of the crane.

15. An operator's cab for a movable overhead material handling apparatus comprising a substantially air-tight tubular member having its side wall structure composed largely of transparent material, means for supporting said member with the longitudinal axis thereof extending vertically, a platform movably connected to said member for rotation about the lower end thereof, a door in the side wall structure providing access for the operator between the interior of the tubular member and said platform, and sealing means cooperating with said member and door to provide a substantially air-tight seal about the door when the latter is closed.

16. An operator's cab for a movable overhead material handling device comprising a substantially air-tight generally cylindrical tubular member closed at both ends and having its longitudinal axis extending vertically and its side wall structure composed largely of transparent material, a platform movably supported by said tubular member for rotation about the exterior thereof, the said tubular member having an aperture providing access for an operator from said platform to the interior of said member, a movable member for closing said aperture, and air conditioning means supported exteriorly of said tubular member and communicating with the interior of said tubular member.

17. In a multi-motored, electrically operated, overhead traveling, material handling apparatus of the character described, a combination of: a movable bridge; a trolley movably supported on said bridge; hoisting mechanism including a load cable carried by said trolley; power means carried by said bridge for moving said bridge; power means carried by said trolley for moving said trolley; power means carried by said trolley for moving said hoisting mechanism; an operator's cab comprising a substantially air-tight generally cylindrical tubular housing closed at

both ends and having the side wall thereof composed largely of transparent material; means suspending said cab from said bridge with the longitudinal axis of said tubular housing extending vertically and said cab offset with respect to the vertical longitudinal centerplane of said bridge so that the load cable of the hoisting mechanism can pass thereby; an operator's seat located in said tubular housing; manually operable controls located in said housing within easy reach of an operator in said seat and fixed with respect to said seat, the said controls being respectively operatively connected with the said power means for moving said bridge, trolley and hoisting mechanism to govern the operations thereof; means providing access between the said bridge and the interior of said housing; and air conditioning means operatively connected with said housing for air conditioning the interior of the latter.

WILLIAM G. WEHR.
